TABLE

Moses Richard Schultz, Barto, Pa., assignor to Art Metal-Knoll Corporation, a corporation of Delaware

Original design application Nov. 8, 1965, Ser. No. 88,044, now Patent No. 211,334, dated June 11, 1968. Divided and this application Oct. 4, 1967, Ser. No. 9,348

Term of patent 14 years

Int. Cl. D6—01
U.S. Cl. D33—14

This application is a division of my copending application, Ser. No. D. 88,044, filed Nov. 8, 1965, for furniture, and now Patent No. D. 211,334.

I claim:

The ornamental design for a table, as shown.
